[57] **CLAIM**

The ornamental design for a panel for partitions or the like, as shown and described.

DESCRIPTION

FIG. 1 is a reduced front elevational view of a panel for partitions or the like showing my new design, the rear being flat and unornamented;

FIG. 2 is a perspective view of the second and third embodiments of the design of FIG. 1 wherein the design of the rear is plain, as shown in FIG. 1, respectively;

FIG. 3 is a reduced side elevational view taken from the right of FIG. 2;

FIG. 4 is a perspective view of a fourth embodiment of the design of FIG. 1 wherein the design of the rear is as shown in FIG. 1;

FIG. 5 is a perspective view of a fifth embodiment of the design of FIG. 1 wherein the design of the rear is plain.

The broken line disclosure of the pedestal feet in FIGS. 2, 3, 4, and 5 is for illustrative purposes only.
